UNITED STATES PATENT OFFICE.

JOHN SMITH, OF KANSAS CITY, MISSOURI.

MANUFACTURE OF RIDGE-CAPS FOR CORRUGATED ROOFING.

SPECIFICATION forming part of Letters Patent No. 317,868, dated May 12, 1885.

Application filed November 3, 1884. (Model.)

To all whom it may concern:

Be it known that I, JOHN SMITH, of Kansas City, Jackson county, Missouri, have invented certain new and useful Improvements in the 5 Manufacture of Ridge-Caps, &c., for Corrugated Roofing, of which the following is a full, clear, and exact description.

The object of my invention is to construct sheet-metal ridge-caps from an integral sheet 10 in such a manner that comparatively watertight joints may be formed between the caps and the underlying corrugated roof-sheets.

My invention consists, principally, as an improvement in methods of abruptly bending 15 corrugated metal sheets across the corrugations thereof, substantially as and for the purposes hereinafter specified.

Reference is to be had to the accompanying drawings, forming part of this specification, in 20 which similar letters of reference indicate corresponding parts in each figure.

Figure 1 is a plan of the upper surface of one of my improved ridge-caps. Fig. 2 exhibits a slight modification in the method of bending the same. Fig. 3 is a half-section upon line *a a*, and the same upon line *b b*, Fig. 1. Fig. 4 is a section through that portion of the sheet coming in contact with the building. Fig. 5 is a section through the apex of a corrugation. Fig. 6 is a perspective view of a 25 varied form of the ridge-cap applied to the roof of a building; and Fig. 7 is a section upon the longitudinal line *f f*, Fig. 2. Figs. 8 and 9 exhibit my improved corrugated sheets inverted and applied to a building in the form 30 of flashings, and Figs. 10 and 11 show the manner in which they are used in the form of gutters and eaves.

Heretofore ridge-caps for corrugated roofing have usually been constructed somewhat 40 of the form shown in Fig. 6; but their overlapping edges were devoid of the corrugations *a*, and their plain surfaces rested upon a lining-strip of wood. This strip was provided 45 with a plain upper surface; but the surface next the roof-sheets, in order to form a joint therewith, was corrugated laterally along the entire length corresponding to the concavities of the said sheets.

50 In constructing my improved ridge-cap I provide a ready-corrugated sheet, *H*, of suitable dimensions, and bend it to any predetermined angle at or near its central line across its corrugations, and in so doing form

a longitudinal bead, *A*, at the apex thereof. 55 It is obvious that in order to do this provision must be made for the lengthening of the sheet along the point of bending—that is, the corrugations at the said point are practically done with and a straight line is formed in the 60 sheet. I accomplish this by forming crimps or raised portions *A'* upon the said bead or apex *A* as it is being formed. These are preferably formed upon a line, *a a* or *d d*, with the convex portions of the corrugations. The 65 said raised portions (as shown in the drawings) taper outwardly from the sides of the bead *A* to a point, as *E* or *B*.

If desired, the bead *A* may be formed with a comparatively abrupt apex, (indicated by *D* 70 in Fig. 1,) and, in a similar manner to the raised portions, terminate at a point, *C*, within the concavities of the corrugations.

In Fig. 7 it will be noticed how the metal is folded at *o* above the bead *A*. By heating 75 the sheet sufficiently before the bending process is begun I am enabled to form a ridge-cap with a plain bead, as shown in Fig. 6.

I prefer that the sheets above described be affixed to the roofs, &c., of buildings by means 80 of the improved fastening-hooks specified in my United States Patent No. 297,862.

Having thus described my invention, I claim as new and desire to secure by Letters Patent—

1. A corrugated sheet of metal for roofing 85 purposes, having a comparatively abrupt bend or bends directly across its corrugations, whereby the converging edges thereof may form any desired angle with each other, substantially as specified.

2. A sheet of metal for roofing purposes, having corrugated sides diverging from an apical bead formed integral therewith, substantially as hereinbefore set forth.

3. The herein-described method of abruptly 95 bending metal sheets laterally to the corrugations thereof, which consists in forming an apical bead where the bend is situated, and of crimping or forming raised portions upon the said bead during the progress of the bending operation, substantially as and for the purposes set forth.

In testimony whereof I affix my signature in presence of two witnesses.

JOHN SMITH.
